UNITED STATES PATENT OFFICE.

AMOS L. SMITH, OF NOKESVILLE, VIRGINIA.

INSULATOR-CLAMP.

1,119,049.

Specification of Letters Patent.

Patented Dec. 1, 1914.

Application filed October 23, 1913. Serial No. 796,792.

To all whom it may concern:

Be it known that I, AMOS L. SMITH, a citizen of the United States, residing at Nokesville, in the county of Prince William and State of Virginia, have invented certain new and useful Improvements in Insulator Clamps, of which the following is a specification.

My invention relates to improvements in clamps to detachably connect a wire with insulators, such as are ordinarily used in stringing telegraph wires.

The invention aims to provide means of the above mentioned character, which are extremely simple in construction, convenient in use, inexpensive to manufacture, self-locking, and will remain in place upon a grooved insulator, without the use of means for holding the same against lateral displacement.

Other objects and advantages of this invention will be apparent during the course of the following description.

In the accompanying drawings forming a part of this specification and in which like numerals are employed to designate like parts throughout the same, Figure 1 is a plan view of a clamp embodying my invention, the same being shown in use, Fig. 2 is a side elevation of the same, Fig. 3 is a plan view of the same showing the parts thereof in an open or partly opened position, Fig. 4 is a perspective view of the clamp removed, Fig. 5 is a plan view of a slightly different form of clamp, and, Fig. 6 is a side elevation of the same.

In the drawings, wherein is illustrated a preferred embodiment of my invention, the numeral 10 designates an insulator, which is preferably cylindrical and is provided near its upper end with an annular groove 11. This insulator may be formed of glass, porcelain or the like, as is well known.

My improved clamp comprises a section 45 of wire 12 or other flexible material, provided between its ends with a looped portion 13, for receiving the wire 14, to be detachably connected with the insulator 10. The section of wire 12 or flexible element is preferably provided at its opposite ends, as more clearly shown in Fig. 4, with eyes or loops 15.

The numeral 16 designates a main preferably approximately L-shaped frame, comprising L-shaped plates 17, which are spaced and superposed, when in use. One end of

the main frame is provided with a reduced hook-extension 18, adapted to enter the annular groove 11. This hook-extension is preferably pivotally connected with one arm 60 of the main frame 16 and when thus pivoted the same is arranged between the L-shaped plates 17 and pivotally connected therewith by means of a transverse pin 19. The reduced hook-extension passes through one of 65 the eyes 15. The arms of the L-shaped plates 17 extend toward the annular groove 11 of the insulator, as shown.

The numeral 20 designates a bell-crank operating lever, arranged between the opposite ends of the L-shaped plates 17, and pivoted thereto, as shown at 21, at a point spaced from the other arm of the same. The arms of this bell-crank operating lever extend toward the annular groove 11 of the insulator. The transverse arm 22 of this lever is apertured, as shown at 23, for receiving the other eye 15, such apertured end being adapted to extend within the annular groove 11.

In the form of the invention shown in Figs. 5 and 6, the reduced pivoted hook-extension 18 is dispensed with, and a reduced hook extension 18' is employed, which is rigidly connected with the end of the frame 16, such reduced hook-extension 75 passing into the annular groove 11, as will be explained.

In the use of the device, the hook-extension is disconnected from the eye 15 so that 80 the same may be applied to the insulator, the flexible element or wire 12 being arranged within the groove 11. This being done, the operating bell-crank lever will assume the outer position, as clearly shown 85 in Fig. 3. The wire 14 may now be passed through the loop 13. The operating bell-crank lever 20 is now swung inwardly toward the insulator, the same being so constructed that its pivot point 21 will be 90 moved past dead center with respect to the apertured end 23, before the longitudinal arm of the bell-crank lever engages the section of wire, as best illustrated in Fig. 1. When the several parts of the device occupy 95 their closed positions, as clearly illustrated in Fig. 1, the reduced hook-extension 18 enters the annular groove 11, while the apertured end 23 of the transverse arm 22 of the operating bell-crank lever 20 also enters the 100 annular groove 11, whereby the entire device 105 is positively held from lateral displacement,

either up or down, without the employment of additional securing means. The operation of the modified form of the invention, shown in Figs. 5 and 6, is identical in all 5 substantial respects with that of the first form of the invention, and it is thought that the same need not be stated.

It is to be understood that the form of my invention herewith shown and described 10 is to be taken as a preferred example of the same, and that various changes in the shape, size and arrangement of parts may be resorted to without departing from the spirit of the invention or the scope of the sub- 15 joined claims.

Having described my invention, I claim:—

1. A device of the character described, comprising a main frame provided at one end with a reduced hook-extension adapted 20 to enter the annular groove of an insulator, a bell-crank lever pivotally connected with the opposite end of the main frame and having its inner end adapted to enter the annular groove of the insulator, and a flexible element adapted to be arranged within the annular groove and connected with the reduced hook-extension and with the inner end of the bell-crank lever.
2. A device of the character described, 30 comprising a main approximately L-shaped frame provided at one end with a reduced hook-extension adapted to enter the annular

groove of an insulator, a bell-crank lever pivotally connected with the opposite end of the main frame and having its inner end 35 adapted to enter the annular groove of the insulator, and a wire connected with said inner end of the bell-crank lever and having its opposite end provided with an eye for detachable connection with the reduced 40 hook-extension of the main frame.

3. A device of the character described, comprising a bell-crank lever having its arms extending inwardly toward an insulator with the inner end of one arm adapted 45 for insertion within the annular groove of the insulator, a main approximately L-shaped frame having its arms extending inwardly toward the insulator, means pivotally connecting one end of the approximately 50 L-shaped frame with the bell-crank lever, a hook-extension pivotally connected with the opposite end of the approximately L-shaped frame and adapted to enter the annular groove of the insulator, and a wire 55 connected with the bell-crank lever and having its opposite end looped for receiving the hook-extension.

In testimony whereof I affix my signature in presence of two witnesses.

AMOS L. SMITH.
